UNITED STATES PATENT OFFICE

MARTIN REAGAN, OF DUNCAN, OKLAHOMA

GAS BURNER

Application filed August 22, 1929. Serial No. 387,699.

This invention relates to a gas burner for use in boilers, furnaces and the like, and it has more particular reference to a structure of this class which is characterized by a novel arrangement and association of parts cooperating intimately in a structural sense for providing a more intense flame, for producing a more uniform flame over a comparatively great area, and for economizing on the use of fuel.

In carrying the invention into effect, I have evolved and produced what I believe to be a new assembly of parts, which are so constructed and co-related as to operate in a more dependable and efficient manner and to better fulfill the requirements of a structure of this class.

The particular details and their specific association and inter-action will become more readily apparent from the following description and drawings.

In the drawings:—

Figure 1 is a top plan view of a gas burner constructed in accordance with the present invention.

Fig. 2 is a longitudinal sectional view thru the same, with portions shown in elevation.

Fig. 3 is an enlarged transverse or cross section on the line 3—3 of Fig. 2, and

Fig. 4 is a plan view of the gas feed or supply insert.

As seen in Fig. 2, the reference numeral 5 designates a relatively large air casing which is provided at longitudinally spaced points with radial openings and outwardly projecting connecting collars 6. Attached to these collars and extending outwardly therefrom in diverging and circumferential spaced relation are the tubular outlets 7. I provide these in groups of three. These constitute the shields as well as the air mixing outlets.

The reference character 8 designates the gas supply pipe which is connected with the internal distributing head or insert. This is in the nature of assemblage of pipes and fittings. For instance, as seen in Fig. 4 there are three pipes 9, 10 and 11 disposed in spaced parallelism. These are connected at one end with elbows 12 which in turn are coupled

with a four-way union 13. The gas supply pipe is connected with this union.

These pipes 9, 10 and 11 are provided with a plurality of longitudinally spaced jets or nozzles and these are all of the same construction and each one comprises a relatively small tubular nipple 14 joined to the pipe through the medium of a suitable coupling 15.

Each nipple is provided with an apertured jet cap 16. The nipples are arranged to telescope over and into the respective or complementary outlets 7 as well seen in the drawings. The nipples are obviously considerably smaller in diameter than the outlet tubes to provide for a desirable admixture of air and gas, and a consequent production of an intense blue blaze or flame.

The reference character 17 clearly designates a hanger which is attached to the casing for suspending the gas feed assembly in the casing. The atmospheric air enters the casing through the opposite ends thereof, and under the draft produced in the outlets 7, mixes with the gas as the gas issues from the jet caps 16.

Thus a highly combustible mixture is had for the production of an intense and economical flame. A careful consideration of the description in connection with the drawings, will enable the reader to obtain a clear understanding of the invention and its features. Therefore, a more lengthy description is regarded as unnecessary.

Minor changes in shape, size, and re-arrangement of details coming within the field of invention claimed may be resorted to in actual practice if desired.

Having thus described my invention, what I claim as new is:—

1. A gas burner, comprising an open ended tubular casing having a plurality of sets of discharge openings surrounded by attaching collars, tubular outlets connected with said collars, said outlets constituting fuel mixers, a gas feed pipe, and a gas distributing and feed assembly in the nature of an insert arranged within said casing and comprising a plurality of horizontally disposed spaced parallel pipes having longitudinally spaced

nipples provided with apertured caps forming nozzles or jets, said nipples projecting telescopically into the complementary outlets and being of a diameter less than the diameter of the outlet to provide for mixing of the gas and air.

2. A gas burner of the type described comprising a hollow elongated casing having open ends, adapted to receive draft air currents, and a plurality of vertical tubes forming mixing chambers and mounted on the casing and communicating therewith and arranged longitudinally and transversely in spaced parallelism, and a unit quickly placeable within and removable from said casing for communicating gas to said chambers, comprising a plurality of parallel longitudinally extending pipes, and a hanger for removably supporting said unit within the casing, a gas supply conduit connected to said unit, and a plurality of upstanding small tubes projecting within said tubes and mounted on said pipes, and communicating therewith, and perforated caps on said small tubes for properly feeding the gas into the draft of air coming through said casing and rising in said tubes.

In testimony whereof I affix my signature.
MARTIN REAGAN.
